UNITED STATES PATENT OFFICE.

FREDERICK GEORGE LAKE, OF PRESTBURY, ENGLAND.

WORKMAN'S TIME-RECORDER.

No. 927,805.

Specification of Letters Patent.

Patented July 13, 1909.

Application filed April 16, 1909. Serial No. 490,292.

To all whom it may concern:

Be it known that I, FREDERICK GEORGE LAKE, a subject of the King of Great Britain and Ireland, and resident of Prestbury, Cheshire, England, have invented a new or Improved Construction of Workmen's Time-Recorders or the Like, of which the following is a specification.

This invention refers to and consists of a new or improved construction of apparatus for recording or registering the time when workmen start and leave off work, or for registering the time of their arrival and departure.

15 The apparatus is of that type which depends for its action on being operated by each workman.

The object of the invention is to provide a construction of time register which is less expensive to make, more simple in construction, and lies in smaller compass than the ordinary known makes of registers.

Upon the accompanying drawings, Figure 1 illustrates a front elevation, and Fig. 2 a right hand side elevation of a workman's time register constructed according to this invention, the outer casing not being shown in order that the main working parts shall be more clearly discernible. Fig. 3 illustrates a vertical transverse section through Fig. 4 of the register, certain of the parts being shown in other than in their normal positions (as hereinafter explained) in order to more clearly demonstrate the action of the register. Fig. 4 illustrates a rear elevation of the register as shown in Fig. 3. Fig. 5 illustrates a side elevation of a detail part seen from the left hand side of the register. Fig. 6 illustrates a face view, and Fig. 7 a vertical sec-

40 tion of certain key-retaining and releasing mechanism hereinafter described. Figs. 8, 9 and 10 illustrate face, edge and plan views respectively of a type-carrying quadrant used in the register. Figs. 11, 12 and 13 illustrate side and end elevations and a plan respectively of certain printing and feed take-up devices. Figs. 14, 15 and 16 illustrate side, edge and plan views respectively of type-carrying levers hereinafter referred 45 to. Fig. 17 illustrates a portion of a strip of paper after passing through the register and

being marked with the necessary data for indicating the time of arrival and departure of a number of workmen.

According to the invention, the improved 55 register consists primarily of what may be termed a key-board 1 forming the front of face of the apparatus. In the said key-board are two rows of holes arranged vertically and parallel to each other, and through 60 such holes loosely projects a series of studs or spindles 2, 2. Applied to the front end of each spindle is a disk or head 3 bearing a numeral, the several spindles and their heads being hereinafter referred to as "keys". In 65 a register designed for registering up to 99 persons, there are nine keys, (1 to 9) in one row, and 10 keys (0 to 9) in the other row, the two rows representing respectively "tens" and "units", see Fig. 1. 70

The numerals on both sets of keys run, by preference, from the top downward. Each hole in the key-board is fitted with a tubular liner 4 and the length of such liner determines the movements of the key. Or such 75 movements are limited by the length of the spindle itself. Upon a fulcrum or axis 5 arranged below the said key-board are two segmental wheels or quadrants 6^a, 6^b, hereinafter called the "numeral" quadrants, one of 80 which lies immediately behind the inner ends of one row of keys, while the other of which lies immediately behind the inner ends of the other row of keys. Upon the periphery of the quadrant 6^a are nine type characters 85 (1 to 9) while upon the periphery of the quadrant 6^b are ten type characters (0 to 9) the numerals starting, by preference, from that end of each quadrant farthest from the key board, see Fig. 4. 90

Alongside the quadrants is a wheel 7 mounted upon a rotating spindle 8, and upon the periphery of such wheel, hereinafter termed the "minute" wheel, are 60 type characters. Such minute wheel is mounted 95 fast on the spindle, and its periphery lies at one point on a level with the peripheries of the numeral quadrants and a given printing line. The said spindle 8 is rotated by a spring motor 9, the action of which is controlled by an escapement electrically actuated once a minute from say the clock by 100

which the workmen's time of arrival and departure is usually calculated. Alongside the minute wheel and loosely mounted on the same spindle, is a further wheel 10 herein-
 5 after termed the "hour" wheel. Such hour wheel on its periphery carries type characters, one to twelve, and its periphery, like that of the minute wheel, at one point lies level with the peripheries of the numeral
 10 quadrants and in a given printing line. Also upon the said spindle 8 is a pinion 11, see Fig. 5 having only a part of its periphery provided with spur teeth. Normally meshing with such teeth are the teeth of a further quad-
 15 rant 12 pivotally mounted alongside the hour wheel. Carried by such further quadrant, hereinafter called the "hour" wheel quadrant, is a knuckle-jointed pawl 13. Upon the hour wheel 10 are twelve teeth 14 with
 20 which the said pawl 13 is designed to engage intermittently and thereby rotate the wheel 10, a twelfth of a revolution at each impulse. The impulses are obtained by the weight of the quadrant itself which after the pinion 11
 25 has moved the hour-wheel quadrant 12 the necessary distance for enabling the pawl 13 to engage one of the ratchet teeth 14, returns the quadrant (by permission of the plain part of the pinion) back to the starting point,
 30 thereby operating the hour wheel. This movement takes place once every hour at the sixtieth minute and brings one of the type characters on the periphery of the hour wheel into a given position. Any reverse
 35 movement of the hour wheel is prevented by a retaining pawl 15 held in play with one of the teeth 14 by a spring 15^a. A spring spur 15^b on the quadrant helps to determine the correct movements of the hour wheel.
 40 Pivottally mounted upon the axis 5 which carries the numeral quadrants, are two bell-crank levers 16^a, 16^b, one arm of each of which extends to a point on a level with the peripheries of the numeral quadrants, while
 45 the other arm extends horizontally to a point in front of the key-board, and there carries a plunger or key 17. Upon that end of one of such levers near the quadrants are type characters suitable for printing the
 50 word "In" and on the same end of the other lever are type characters suitable for printing the word "Out". Upon the respective keys 17 of such levers the same words are printed. The keys will preferably be in the form of
 55 spindles with disk heads and the spindles will pass loosely through the lever ends, which are forked or slotted, and through a horizontal extension 1^a of the key-board.
 60 Adjacent to the peripheries of the quadrants and wheels is an arrangement of printing mechanism by which, when it is operated, an impression of the type on the quadrants, levers and wheels may be taken on a

strip of paper. In one arrangement such mechanism may consist of a roller 18 rotatably mounted in brackets 19 above the numeral quadrants and wheels. Between such roller and the type faces will pass a strip of paper, the roller having pins and (or) being roughed (milled), and also having flanges by 70 which the paper may be advanced and guided as the roller rotates. The paper will be drawn from a reel 20 and led between a roller 18^a and the roller 18 before passing over the type, and after leaving the type is 75 delivered by preference, loosely into a receiver, or, if desired, on to another reel. Also passing between the roller and type faces is an inked ribbon, or a transfer copy-
 80 ing strip or the like. In the case of a ribbon 85 it will preferably be endless (see Fig. 4) and be arranged transversely of the peripheries of the quadrants. To the rear of the said paper-carrying roller 18 is a lever or presser-printing arm or bar 21, which is suitably ar-
 85 ranged to press the paper against the ribbon and type, see Fig. 3. This printing bar is left free and operated by means of a spring-
 90 returned rod 22 slidably mounted in bearings 23, a plate 24 connected to the rod and acted upon by the keys 17, and a bracket 25 ad-
 justably mounted on the rod 22. Carried by this bracket is a spring blade 26 which presses upon the printing bar 21 and nor-
 95 mally tends to force it against the type faces 95 of the quadrants. Upon one of the brackets 19 by which the printing bar 21 is pivotally carried is a short pendent lever arm 27 in which is a notch or recess 28. Upon the printing bar is a pin 29 which, with the parts 100 in their normal position, engages the recess 28 in the lever arm 27. Upon the bracket 25 is a small bent wire extension 30 which ex-
 105 tends below the printing bar, and when the bracket 25 is in its highest position, holds the printing bar 21 elevated and clear of the quadrants. Upon the bracket 25 is also a 110 small spur or wire finger 31, which lies im-
 mediately above and in the plane of the lever arm 27. When the bracket 25 is lowered to 115 operate the printing bar, the movement of the printing bar is arrested by the pin 29 until the finger 31 meets and presses against the lever arm 27, which, being then forced back, releases the pin 29 and allows the 120 printing bar, under the impulse of the spring 26 to sharply strike the paper and produce the desired impression, the wire extension 30 extending down below and beyond the type faces at the moment the impression is taken. Upon the bracket 25 rising again, the wire extension 30 meets and raises the printing bar and carries the pin 29 back into the re-
 125 cess of the lever arm 27, in which it remains until the next printing operation.
 In order that in descending they shall be

free to operate both the type levers 16^a, 16^b, and the printing bar 21, the keys 17 act upon the levers through springs 32.

Upon one end of the axis of the paper 5 guide roller 18 is a wheel 33 with ratchet or like teeth and upon the bracket 25 is a pawl 34 so shaped and placed that, when the printing bar is operated (moved toward the type), it (the pawl) slips over a tooth of the 10 wheel, and, on the printing bar making its return movement, the pawl rotates the wheel one tooth and thus advances the paper. A spring influenced pawl 35 serves to prevent the wheel rotating backward.

15 The use of the improved register may be briefly described as follows:—The workman on arrival presses in the key or keys representing his number, thereby pushing the numeral quadrant or quadrants 6^a 6^b backward 20 and causing the type character on each, corresponding to the numbers on the keys pressed in, to come below the printing bar, means of a known type such as a small notch 36 in each key spindles (see Fig. 6) and spring- 25 pressed latching levers 37, see Figs. 6 and 7, preventing the keys and quadrants returning. The workman then depresses the plunger key 17 bearing the word "In", the early movement of which brings the type 30 lever 16^a below the printing bar and in line with the numerals on the numeral quadrants to be printed. The further or continued downward movement of the "In" plunger key 17 then sharply operates the printing 35 bar, which causes the paper to be printed with the workman's number, with the word "In" and also owing to the type on the hour, and minute wheels also coming below the printing bar with the time of his arrival.

40 Upon being released the "In" plunger key under the influence of spring 32 and the weight of the lever 16^a rises up and resumes its normal position, the printing bar 21 at the same time, under the influence of the 45 spring 22^a, also returning to its original position. To release the key-board keys and thus allow the numeral quadrants to return to their normal positions, use is made of a 50 slide bar 38 mounted in guides 39 and carrying lateral projections 40, see Fig. 6, one for and lying immediately adjacent to each latching lever 37. To operate the slide bar 38, use is made of the rod 22 and a lever 42, the slide bar being held normally elevated by 55 a spring 43, see Fig. 3, and the lateral projections 40 lying above the free ends of the latching levers. The quadrants will move back under the influence of springs 41.

When the workman leaves off work, say at 60 breakfast, dinner or tea time, he again first presses in the key-board key or keys corresponding to his number. He then depresses the plunger key 17 bearing the word "Out"

thereby bringing the type lever 16^b into use, and then by the further depression of the 65 plunger key, causing the printing bar to print his number, time of departure, and the word "Out" upon the strip of paper. The return of the plunger keys, lever and quadrants is effected in precisely the same manner as in the case of the previously described operations.

In Fig. 3 the parts are shown in the position they occupy when the key 5 of the left hand column and the key of the right hand 70 column have been pushed in, and also when the "Out" key 17 has been depressed and the printing arm has just struck the paper. Key 5 of the right hand column is shown removed in order not to confuse the illustration of key 5 of the left hand column.

A portion of the strip of paper printed with the times of arrival and departure, the words "In" and "Out" and the workmen numbers is shown in Fig. 17.

The minute wheel 7 is preferably controlled electrically from the nearest available clock through a suitable escapement, the electric circuit being completed at each minute, and the wheel 7 therefore only moving at each minute.

The forward movements of the levers 16^a, 16^b are limited by suitable stops. The inked ribbon passes between a rubber-faced wheel 44 and milled spindle 45, this latter being 95 carried by a fixed tubular bracket 46, and the former being carried by a pivoted axis 47 which is yieldingly forced toward the bracket 46 by a spring arranged within a slotted guide 48. Upon the spindle 45 is a ratchet 100 wheel 49 and upon the rod 22 is a spring-pressed pawl 50 which presses against the teeth of the wheel 49, see Fig. 4. Also engaging the teeth of such wheel is a spring retaining pawl 51. With each upward movement 105 of the rod 22 after each printing operation, the wheel 49 is advanced a small portion of a revolution, thereby advancing the ribbon and causing it to present a fresh surface to the type at each printing operation.

The paper reel 20 is preferably carried between cones, at the ends of the spring extensions 19^a of the brackets 19, the cones offering a slight "drag" and the arms allowing of the ready insertion and withdrawal of the 115 reel.

To afford stiffness the quadrants 6^a, 6^b may be formed with a lateral web 6^c, see Fig. 9.

The printing bar has a wire guide 52 for 120 the paper to pass through after being printed.

What I claim is:—

1. A workman's time recorder comprising, in combination, a vertical and perforated key-board, a fulcrum and supporting means 125 therefor behind the keyboard, quadrants

mounted upon such fulcrum and adapted to lie with one edge normally parallel with the rear face of the keyboard, numeral type characters on the curved peripheries of the quadrants, two independent levers also mounted on the said fulcrum behind the said keyboard and alongside the quadrants, and one of such levers bearing the type characters of the word "In" and the other of such levers bearing the type characters of the word "Out" and both the said levers holding the said type characters on a level with the type characters on the quadrants and normally to one side of a printing line, two wheels and an axis therefor behind the keyboard and alongside the levers, type characters of the hour of the day on one wheel and type characters of the minutes of the hour on the other wheel, means for rotating such wheels at a rate proportionate to the time of the day, a series of plunger keys slidably fitting the perforations in the keyboard and each having a disk at one end bearing a numeral and at the other end lying directly in front of one of the quadrants, means for normally holding the quadrants against the plunger ends, means for returning the plunger keys after being pressed against the quadrants, means whereby on the plunger keys being pushed one by one against the quadrants these latter are moved on their fulcrum to various distances, spring-actuated retaining pawls—one for each plunger in which is a notch—and supporting means for the pawls, a printing bar, means for supporting such bar elastically above the quadrants, levers and wheels, an inked ribbon passing between such bar and the quadrants, means for depressing the printing bar, means for retaining the bar momentarily when being depressed and suddenly releasing the same, and further means whereby after the bar has moved to strike the type, the retaining pawls of the plunger keys are simultaneously moved and caused to free the plunger keys, substantially as herein set forth.

2. A workman's time recorder comprising, in combination, a vertical and perforated keyboard, a fulcrum and supporting means therefor behind the keyboard, quadrants mounted upon such fulcrum and adapted to lie with one edge normally parallel with the rear face of the keyboard, numeral type characters on the curved peripheries of the quadrants, a series of plunger keys slidably fitting the perforations in the keyboard and each having a disk at one end bearing a numeral

and at the other end lying directly in front of one of the quadrants, means for normally holding the quadrants against the plunger ends, means for returning the plunger keys after being pressed against the quadrants, means whereby, on the plunger keys being pushed one by one against the quadrants, these latter are moved on their fulcrum to various distances, spring-actuated retaining pawls, one for each plunger in which is a notch, and supporting means for the pawls, a printing bar, means for supporting such bar elastically above the quadrants, an inked ribbon passing between such bar and the quadrants, means for depressing the printing bar, means for retaining the bar momentarily when being depressed and suddenly releasing the same, and further means whereby after the bar has moved to strike the type, the retaining pawls of the plunger keys are simultaneously moved and caused to free the plunger keys, substantially as herein set forth. 85

3. A workman's time recorder comprising, in combination, a vertical and perforated keyboard, a fulcrum and supporting means therefor behind the keyboard, quadrants mounted upon such fulcrum and adapted to lie with one edge normally parallel with the rear face of the keyboard, numeral type characters on the curved peripheries of the quadrants, two independent levers also mounted on the said fulcrum behind the said keyboard and alongside the quadrants, and one of such levers bearing the type characters of the word "In" and the other of such levers bearing the type characters of the word "Out" and both the said levers holding the said type characters on a level with the type characters on the quadrants, and normally to one side of a printing line, a series of plunger keys slidably fitting the perforations in the keyboard and each having a disk at one end bearing a numeral and at the other end lying directly in front of one of the quadrants, means for normally holding the quadrants against the plunger ends, means for returning the plunger keys after being pressed against the quadrants, means whereby on the plunger keys being pushed one by one against the quadrants these latter are moved on their fulcrum to various distances, spring-actuated retaining pawls, one for each plunger in which is a notch, and supporting means for the pawls, means for rocking each of the said type-carrying levers about its fulcrum, and further means operated by the said lever-actuating mechanism for simultaneously depressing the printing bar, means for retaining the bar momentarily when being depressed and suddenly releasing the same, and further means whereby, on either of the said type-carrying levers being operated to move the printing bar and after the bar has moved to strike the type, the retaining pawls of the plunger keys are simultaneously moved and caused to free the plunger keys, substantially as herein set forth. 110

4. A workman's time recorder comprising, in combination, a vertical and perforated

keyboard, a fulcrum and supporting means therefor behind the keyboard and levers mounted on said fulcrum, one end of each of which extends upward and carries type characters and the other end of each of which extends horizontally, and means for actuating such levers independently of each other whereby they are normally held out of a given printing line and whereby they may be moved into such printing line, substantially as herein set forth.

5. A workman's time recorder comprising,

in combination, a vertical keyboard, a printing bar, means for supporting such bar elastically, means for depressing the printing bar, means for retaining the bar momentarily when being depressed and suddenly releasing the same, substantially as herein set forth.

10
